FEED COVER-PLATES FOR SEWING MACHINES

John P. Enos, Union, N.J., assignor to The Singer Manufacturing Company, Elizabeth, N.J., a corporation of New Jersey

Filed Feb. 15, 1955, Ser. No. 488,215

3 Claims. (Cl. 112—260)

This invention relates to devices in the nature of an attachment adapted to be applied to a sewing machine and, more particularly, to improvements in feed cover-plates, i.e., work-supporting plates adapted to be applied over the work-feeding dogs of a sewing machine so as to render these usual sewing machine work-feeding instrumentalities ineffective.

Feed cover-plates find utility in readying a sewing machine for stitching operations in which the usual work-feeding instrumentalities are unsuitable, e.g., as during embroidery stitching where by manual shifting of the work fabric the operator may produce a stitch pattern beyond that obtainable with use of the sewing machine work-feeding mechanism; or as when a supplemental device is applied to the sewing machine, such as a hemstitching attachment in which all necessary feeding movements of the work fabric are imparted by the attachment.

It is an object of this invention to provide a feed cover-plate which is formed in a novel manner to cooperate advantageously with fabric shifting means other than those of the sewing machine.

A further object is to provide a feed cover-plate which is adapted to cooperate with a hemstitching attachment to enhance the effectiveness of operation of the attachment in a novel manner.

It is a further object of this invention to provide an attachment fastening device which may be readily and conveniently applied or detached from a sewing machine.

With the above and additional objects and advantages in view as will hereinafter appear, this invention comprises the devices, combinations and arrangements of parts hereinafter described and illustrated in the accompanying drawings of a preferred embodiment in which:

Fig. 1 represents a head end elevational view of a portion of a sewing machine having a hemstitching attachment of well known construction operatively positioned thereon, and to which my improved feed cover-plate has been applied;

Fig. 2 represents a top plan view of the feed cover-plate of this invention including a portion of the sewing machine and indicates in dot-and-dashed lines portions of the hemstitching attachment of Fig. 1; and

Fig. 3 represents a cross-sectional view taken substantially along lines 3—3 of Fig. 2.

Referring more particularly to the drawings, the sewing machine frame is formed with a bed 11 having a flat cloth supporting upper portion or plate 12. As shown in Fig. 1, the sewing machine is provided with conventional stitch-forming instrumentalities including a needle 13 secured in an endwise reciprocable needle bar 14 which is carried by a bracket arm portion (not shown) of the sewing machine frame, and cooperates in the formation of stitches with a shuttle 15 which is journaled beneath the bed for oscillation in timed relation with reciprocation of the needle as is well known in the art. Operating from beneath the bed upwardly through suitable aper-

2

tures in a throat-plate 16 fitted in the cloth support 12 of the machine frame is a feed-dog 17 which, during normal operation of the sewing machine in the absence of a feed cover-plate, serves to advance the work past the stitch-forming instrumentalities to form a line of stitches.

Also carried in the bracket arm portion (not shown) of the machine frame is a presser bar to which is secured, as best illustrated in Fig. 1, a hemstitching attachment 18 provided with a forked actuating lever 19 disposed to embrace a needle clamp 21 on the needle bar 14. The hemstitching attachment is of the type disclosed in the U.S. patent of Hinman et al. No. 2,069,652, Feb. 2, 1937, to which patent reference may be had for a detailed description thereof. For an understanding of the present invention, it will be sufficient to understand that the hemstitching attachment includes a presser member 22 and a feeding member formed with spaced work-engaging fingers 23—23 disposed one at each side of the presser member. The presser and feeding members of the attachment are alternately moved into engagement with the work fabric, the presser member serving to clamp the work in place during stitching at which time the return stroke of the feeding member occurs while the work-engaging fingers are raised clear of the work. The hemstitching attachment also includes a piercer member 24 which is periodically depressed and passes through an enlarged slot 25 in the presser member so as to form an opening in the work fabric about which a subsequent group of stitches may be made to form a hemstitch pattern.

Since the hemstitching attachment thus provides a complete mechanism for feeding the work fabric, the action of the sewing machine feed-dog 17 becomes not only unnecessary but undesirable. For the purpose of rendering the feed-dog ineffective, a feed cover-plate, indicated generally as 26, is provided. The feed cover-plate is preferably formed with a rim portion 27 adapted to bear against the cloth supporting plate 12 and to sustain a raised flat feed cover portion 28 adapted to overlie the sewing machine throat-plate and feed-dog. The presser member 22 and work-engaging fingers 23—23 of the hemstitching attachment are adapted to bear upon the work supported on the raised sheet metal portion 28 of the feed cover-plate generally in the positions shown in dot-and-dashed lines in Fig. 2, the raised feed cover portion 28 being formed with apertures 29 and 30 to accommodate, respectively, the piercer 24 and the needle 13.

Extending from the rim portion 27 is an arm 31 provided with a channel 32 preferably in the form of an elongated slot which is formed with sufficient clearance to admit freely the threaded portion of a pair of cover-plate securing screws 33 which are adapted to be threaded into tapped holes, as at 34, provided in the cloth-supporting plate 12 of the bed. In the past, these fastening screws have presented a nuisance and a problem which, until the present invention, has not been satisfactorily solved. If ordinary fastening screws are used, they are certain to become lost or misplaced among the countless number of similarly small articles which invariably accumulate in a sewing storage box. It has been known to form a neck between the threaded portion of the fastening screw and its head and thereby to maintain the screw captive directly in an elongated slot, such as the channel 32 of arm 31. This practice is theoretically satisfactory but proves to be particularly unsatisfactory in practice because it is undesirable owing to the thickness of the bed-portion 12 to make the necked portion long enough to permit either of the screws to be tightened or removed in one operation. Unless the screws are

tightened or loosened together, that is, by alternately turning each a fraction of a turn, the slotted arm will be tilted and possibly bent and the assembly will either bind tightly or the threads will be stripped.

The present invention not only solves the problem, but it also provides other novel advantages of convenience in use. The fastening screws 33, as best illustrated in Fig. 3, are each formed with a necked portion 35 between the threaded shank and an enlarged head 36. The fastening screws are held captive each at the extremity of a respective one of the resilient arms 37-37 of a fastening screw retainer member 38. For this purpose, the free extremity of each resilient arm is formed with a keyhole-shaped slot 39-39 which may be deformed to admit the necked portion 35 of a fastening screw. The screw retaining member 38 is formed with an elongated aperture 40 which is secured loosely by a rivet 41 to the arm 31 of the cover-plate 26 so that the fastening screws are permanently captive with respect to the feed cover-plate and cannot become lost or misplaced. The retainer member 38 maintains the fastening screws in a predetermined spaced relationship along the channel 32 in the arm 31 corresponding to the space between tapped holes 34 formed in a conventional sewing machine cloth plate. Thus, when one of the screws 33 is aligned with one of the tapped holes, the other will also be properly aligned. The separate arms 37-37 of the screw retaining member are quite flexible and permit each of the fastening screws to be individually tightened or removed in turn, and alleviate completely the possibility of binding during the application or removal of the attachment to the machine.

During the course of stitch formation when the feed cover-plate 26 is being used, there are intervals during which the work fabric may be shifted. At other periods, however, it is of the utmost importance to high quality stitch formation that the work fabrics be held stationary and clamped securely in this position. Referring more particularly to the hemstitching attachment illustrated in the drawings, it is the function of the feeding fingers 23 to advance the fabrics with respect to the stitch-forming instrumentalities and, therefore, the feed cover-plate beneath the feeding fingers is smooth and highly polished. It has been the practice in the art to make the entire surface of the coverplate smooth for this purpose, however, such construction reduces the effectiveness of the presser member 22 which serves to clamp the fabric in place during the nonfeeding intervals of the stitching cycle. If the fabric slips between the presser member and the cover-plate as, for instance, during penetration and withdrawal of the needle, the loosened fabric will permit flagging to occur, that is, the loose fabric will be carried upwardly and downwardly with the needle, resulting in the possible skipping of stitches or the erratic and imperfect formation of some of the stitches. Equally objectionable is flagging of the loose fabric under the action of the piercer 24. The action of both the needle and the piercer is to stretch a hole in the fabric, and such stretching, which is more pronounced under the action of the piercer because of its larger diameter, gives rise to considerable friction therebetween. If the fabrics are not clamped securely, they will be carried with the piercer which will then produce a ragged-edged imperfect hole in the fabrics rather than the desired clean-edged variety.

In order to eliminate slippage of the fabrics beneath the presser member 22, the surface of the cloth plate in this vicinity has been roughened in a particularly effective manner. The extent of the roughened area, as indicated at 50 in Fig. 2, is preferably at least coextensive with the vertically projected outline of the presser member 22 of the hemstitch attachment. The remainder of the cover plate surface may remain smooth so as to preserve the effectiveness of the feeding fingers 23-23.

The surface of the area 50 is preferably roughened in

a completely random fashion so as not to favor slippage of the fabric in any direction. While it is important that the area 50 be roughened, it is desirable that the roughness be not excessive otherwise the normal advance of the work by the attachment feed will not be uniform. In other words, it is important that the degree of roughness be such as to eliminate inadvertent slip of the fabric yet will permit uniform feeding of the fabric past the stitching instrumentalities. A surface 50 provided as a result of sandblasting has been found to be particularly well suited for this purpose.

Having thus set forth the nature of the invention, what I claim herein is:

1. A feed cover-plate for a sewing machine having a frame provided with a pair of tapped attachment fastener securing holes, said feed cover-plate being formed with an arm having opposite sides of which one side is adapted to abut said sewing machine frame, a pair of fastening screws each having a threaded shank formed with a narrowed neck portion, said feed cover-plate arm being formed with an elongate aperture, said elongate aperture having a width slightly larger than the diameter of the threaded portions of said fastening screws, said fastening screws each being disposed for axial movement through said elongate aperture, a fastening screw retainer secured to said feed cover-plate arm at a point remote from said elongate aperture therein and at the side of said arm opposite that which is adapted to abut said sewing machine frame, and a pair of separate resilient members carried by said fastening screw retainer, each of said resilient members being bifurcated and formed with a keyhole shaped space between bifurcations, of which keyhole shaped space the narrowest portion has a width less than the diameter of the necked portion of said fastening means and the widest portion has a width less than the diameter of the threaded shank and greater than the diameter of said necked portion of said fastening screws each to embrace the necked portion of one of said fastening screws over the elongate aperture of said feed cover plate arm.
2. A device for fastening an attachment formed with an aperture to a sewing machine having a tapped hole formed therein, comprising a fastening screw having a threaded shank of sufficient size and shape in cross-sectional dimensions to be accommodated in said attachment aperture with slight clearance on all sides, said threaded shank being disposed for axial movement through said attachment aperture, a narrowed neck portion formed on said threaded shank, a resilient member formed with an open ended keyhole shaped slot disposed to embrace the narrowed neck portion of said fastening screw, said keyhole shaped slot having at the widest portion a width less than the diameter of said threaded shank and at the narrowest portion a width less than the narrowed neck portion of said threaded shank, said resilient member being deformable to open the narrowest portion of said keyhole shaped slot for passage of the narrowed neck portion of said fastening screw into the widest portion of said keyhole shaped slot, and means for securing said resilient member to said attachment at a point remote from said aperture with the widest portion of said keyhole shaped slot disposed over said attachment aperture.
3. A device for fastening an attachment formed with an elongate aperture to a sewing machine frame having a pair of tapped holes formed therein, comprising a pair of fastening screws each having a threaded shank with a diameter smaller than the width of said attachment aperture, the threaded shanks of said fastening screws each being disposed for axial movement through the elongate aperture of said attachment, a narrowed neck portion formed on the threaded shank of each of said fastening screws, a fastening screw retainer, means for securing said retainer to said attachment at a point remote from said elongate aperture therein, and a pair of

separate resilient members carried by said fastening screw retainer, each of said resilient members having bifurcated portions defining therein open ended keyhole shaped slots, said bifurcated portions being deformable to widen the keyhole shaped slots for insertion of a fastening screw from the open end thereof and dimensioned in the undeformed state each to embrace the necked portion of one of said fastening screws above the elongate aperture of said attachment.
